(57) **CLAIM**

I claim the ornamental design for a condom in the shape of a dolphin, as shown and described.

DESCRIPTION

FIG. 1 is a side view of the dolphin shaped condom according to the design;

FIG. 2 is a top view of the design;

FIG. 3 is a bottom view of the design;

FIG. 4 is a side view of another embodiment of the dolphin shaped condom according to the design;

FIG. 5 is a top view of the design shown in FIG. 4; and,

FIG. 6 is a bottom view of the design shown in FIG. 4.
